STUART BALLANTINE, OF MOUNTAIN LAKES, NEW JERSEY, ASSIGNOR TO RADIO CORPORATION OF AMERICA, A CORPORATION OF DELAWARE

METHOD OF AND APPARATUS FOR FORMING GRID ELECTRODES

Application filed June 16, 1931. Serial No. 544,801.

This invention relates to the formation of grid electrodes for vacuum tubes, and particularly to methods of and apparatus for forming grid electrodes having different operating characteristics at different portions of the grid structure.

In the commercial production of vacuum tubes it has been the standard practice to employ grids in the form of a helical winding 10 which is secured to and supported by one or more wires that extend axially of the helix and tangent to the turns thereof. Poly-mu tubes having the operating characteristics described in the "Proceedings of the Institute of Radio Engineers, December, 1930, 15 pages 2102 to 2127" have employed control grid windings of variable diameter and/or pitch, as well as windings of uniform pitch from which one or more turns were removed.

20 According to the present invention, grids of the type employed in poly-mu tubes are prepared by first forming the grid as a helical winding, preferably of constant pitch, and then bending one or more of the turns out of the helical surface.

Objects of the invention are to provide methods of and apparatus for forming grid electrodes by the deformation of a helical grid winding. Further objects are to provide 30 a method and apparatus of the type stated in which the deformation is effected by forcing one or more wedge shaped blades into or through parts of the helical grid winding, thereby bending some of the turns aside.

These and other objects of the invention will be apparent from the following specification, when taken with the accompanying drawing, in which:

40 Fig. 1 is a perspective view illustrative of the invention; the grid and presser bars being shown in their relative positions prior to the deformation of the grid winding;

Figs. 2 and 3 are fragmentary longitudinal 45 sections showing, respectively, presser bars fully entered into, and withdrawn from, the grid;

Figs. 4, 5 and 6 are front, end and top views, respectively, of one form of apparatus suitable for forming the grids;

Figs. 7 and 8 are end and top views of another embodiment; and

Fig. 9 is a section taken on line 9—9 of Fig. 7.

The grid shown in Fig. 1 is of the type employed in many styles of vacuum tubes now manufactured commercially, and consists of a pair of supporting wires 1 upon which a finer wire 2 is wound as a helix of uniform pitch. Both hand-operated and automatic 55 machines for winding such grids and for welding the helical winding 2 to the supporting wires 1 are well known in the industry.

According to the present invention, a helical grid winding of this known type may be 60 given a desired form for inclusion in a poly-mu tube by reforming some of the turns of the helix by spreader bars 3 that are forced between adjacent turns of the winding to bend a plurality of turns, or fractional turns 65 of the winding, axially of the grid.

As shown in Fig. 2, oppositely disposed spreader bars 3, 3' have been moved into the winding to bend aside a plurality of turns at each side of the spreader bars. Upon removal 70 of the spreader bars, as shown in Fig. 3, the resiliency of the winding 2 permits the bent turns to spring back to some extent. In the design of apparatus for shaping the grids, this effect may be compensated by making the 75 spreader bars oversize to a greater or less extent in accordance with the resiliency of the winding.

One form of apparatus suitable for carrying out the process is illustrated in Figs. 4, 5 and 6. A supporting frame 4 carries a mandrel 5 over which a grid such as shown in Fig. 1 may be placed, the frame having perforations 6 for receiving the ends of wires 1 which project beyond the helical winding 2. Upper and lower sets of spreader blades 3, 3' are carried by a pair of levers 7 which are pivoted upon a shaft 8 and normally held apart by a spring 9. As best shown in Fig. 6, the bars 3 and 3' are inclined in opposite directions to permit the spreader bars to slide between adjacent turns of the winding. The parts of the apparatus are so proportioned that, when the grid is slid as far as possible 95 upon the mandrel 5, the spreader bars are 100

aligned with gaps between adjacent turns. In forming a grid, the wire 2 is wound upon and secured to the supporting wires 1 by hand or automatic grid-forming machines of known types. The helically wound grid is then slipped upon the mandrel 5 of the forming machine, with the end turn of the winding 2 resting against the face of the frame 4, or with the ends of supporting wires 1 seated against the ends of perforations 6. The operator presses the lever 7 together to force the spreader blades 3, 3' into the winding and, upon releasing the pressure, the levers open to permit removal of the finished grid.

In place of moving the edges of the spreader blades radially of the wind, these edges may move along chords of the winding to bend the turns axially of the grid. One form of apparatus employing this method is illustrated in Figs. 7 to 9, inclusive. The apparatus includes a suitable base or supporting structure 10 for the post 11 which carries a mandrel 12 for receiving the grid blanks. Recesses 13 are provided in the post 11 for receiving the ends of the supporting wires 1 of the grid blanks. The spreader blades 14 project downwardly from a slider 15 which has a dove-tail engaging a correspondingly shaped slideway 16 on the post 11.

To shape a grid, the operator raises the slider 15, slips a grid blank upon the mandrel 12 and depresses the slider to force the knife-shaped spreader bars 14 through the helical grid winding. In Figs. 7 and 9, the dotted lines 2' indicate the position of the helical winding when the grid blank is placed on the mandrel. If desired, spring means may be provided for normally holding the slider 15 in raised position but the slider 15 is of such small size and light weight that no difficulty or delay is experienced when it is raised manually.

Apparatus such as shown in Figs. 4, 5 and 6 may be provided with interchangeable levers 7 which carry various styles and arrangements of spreader blades. Different combinations of such levers may then be employed to obtain final grid structures of substantially different forms and electrical properties. Interchangeable slides provided with different combinations of spreader blades may be provided for the other type of bending machine.

While I have illustrated but one form of grid electrode having bent turns, it will be apparent that any number of turns or fractional turns of the original helical winding 60 may be displaced by appropriate choice of the number and relative size of the spreader blades. As indicated in Fig. 1, all of the bent sections may be located at one side of the grid when the helical winding is carried 65 by two or more supporting wires.

I claim:

1. The process of forming a vacuum tube grid which comprises the steps of first forming a helical winding and securing each winding thereof to supporting wires, and then forcing a spreading tool between adjacent turns of said winding to deflect portions thereof axially of the grid structure while maintaining the contacts between the grid wire and the supporting means fixed. 75

2. Apparatus for forming grids, comprising a support for holding a grid blank in the form of a helical winding, means cooperating with said support to insure a predetermined positioning of a grid upon said support, and a spreader blade movable with respect to said support and along such path that said blade will enter between adjacent turns of a grid when the same is held by said support. 80

3. Apparatus for forming grids, comprising a frame, a mandrel thereon for receiving a grid blank in the form of a helical winding, a pair of oppositely disposed spreader blades, and means supporting said blades on said frame for movement towards and away from said mandrel. 85 90

4. Apparatus for forming grids, comprising a frame, a mandrel on said frame for supporting a grid blank in the form of a helical winding, a lever arm pivotally mounted on said frame, and a spreader blade on said lever, said blade being adapted to slide between adjacent turns of a grid blank mounted on said mandrel. 95

5. The invention as set forth in claim 3, 100 wherein said supporting means comprises a slider carrying said spreader blades, and a slideway on said frame, said slider being movable upon said slideway.

6. In the art of forming vacuum tube grids wherein a grid wire is wound in the form of a helix and secured to a supporting wire at a point in each turn of the helix, the method of changing the characteristics of the grid after it is wound and attached to the supporting wire which comprises applying pressure between adjacent turns of the helical winding at unsecured points thereof to bend the grid wire at the points of support and thereby displace portions of the helical winding axially of the grid structure while maintaining the points of support of the grid wire on the supporting wire intact. 110 115

7. In the art of forming vacuum tube grids wherein a grid wire is wound in the form of a helix and secured to a supporting wire at a point in each turn of the helix, the method of changing the characteristics of the grid after it is wound and attached to the supporting wire which comprises, spreading the wound structure intermediate the points of support so as to maintain uniform density of windings per unit length at the points of support and non-uniform density of windings per unit length at unsupported points 120 125 130

along certain portions of the grid structure.

8. The method of changing the characteristics of a vacuum tube having a cathode and anode between which is a grid structure formed from a multi-turn helical winding attached at diametrically opposite points in each turn of the helix to supporting means which comprises spreading certain adjacent turns of the helix at points intermediate each 10 support point thereof so that the turns are distorted from the position of winding and utilizing the resilience of the material to maintain after spreading a variable concentration of helical turns per unit axial length 15 thereof so that when signals are applied between the grid and cathode electrodes the electron flow toward the anode varies throughout the length of the grid in accordance with the concentration of the helical 20 turns.

9. The method of converting a grid structure which has been formed by winding grid wire into a helix of substantially constant pitch about a support means and in which 25 each turn is fixed to the support means, for use in a poly-mu tube which comprises displacing portions of the helical windings at unsupported points so as to maintain substantially uniform density of windings per 30 unit length axially along the points of support and non-uniform density of windings per unit length at other points of said windings.

STUART BALLANTINE.
